STEP LADDER

Edward J. Savrsnik, Sheboygan, Wis.

Application August 24, 1955, Serial No. 37,638

Term of patent 7 years

(Cl. D15—8)

I claim:

The ornamental design for a step ladder, as shown.
